UNITED STATES PATENT OFFICE.

RALPH D. HOWELL, OF NEWARK, NEW JERSEY.

STRETCHING AND IRONING TABLE FOR LAUNDRIES.

1,104,507.

Specification of Letters Patent. Patented July 21, 1914.

Application filed December 15, 1913. Serial No. 806,688.

To all whom it may concern:

Be it known that I, RALPH D. HOWELL, a citizen of the United States, residing at Newark, in the county of Essex and State 5 of New Jersey, have invented certain new and useful Improvements in Stretching and Ironing Tables for Laundries; and I do hereby declare the following to be a full, clear, and exact description of the invention, such as will enable others skilled in the art to which it appertains to make and use the same, reference being had to the accompanying drawings, and to characters of reference marked thereon, which form a part 10 of this specification.

This invention has reference, generally, to improvements in laundry appliances; and, the invention relates, more particularly, to a novel construction of ironing table having 20 clamping and stretching devices connected therewith for holding and stretching articles to be ironed upon said table.

The present invention has for its principal object to provide a combined ironing 25 and stretching table for laundry use, by means of which large flat pieces, such as lace-curtains, and similar articles, may be properly and uniformly stretched, and then held upon the table ready for the application 30 of the heated smoothing irons.

The invention has for a further object to provide in connection with an ironing table clamp-means for grasping and holding the article to be ironed, together with means 35 for moving one of said clamp-means whereby the article secured by said clamp-means may be properly and uniformly stretched.

A further object of the said invention is to provide said ironing table with properly 40 arranged gage means, which serve as guides for the proper laying out and positioning of the articles to be stretched and ironed upon the table.

Other objects of this invention, not at this 45 time more particularly enumerated, will be clearly understood from the following detailed description of the present invention.

With the various objects of the present invention in view, the same consists, primarily, in the novel combined stretching and ironing table hereinafter set forth; and, the invention consists, furthermore, in the novel arrangements and combinations of the several devices and parts, as well as in the 50 details of the construction of the same, all

of which will be more fully described in detail in the following specification, and then finally embodied in the claims which are appended to and which form an essential part of the said specification.

The invention is clearly illustrated in the accompanying drawings, in which:

Figure 1 is a side elevation of the novel combined stretching and ironing table made according to and embodying the principles 60 of my present invention. Fig. 2 is a plan view of the same. Fig. 3 is a large detail cross section of the same, taken on line 3—3 in said Fig. 1, looking in the direction of the arrow α . Fig. 4 is a detail cross section, 65 showing one side of the table and a clamping-device, together with a holding or positioning means, moved into operative position with relation to the receiving surface of said ironing table. Fig. 5 is a detail 70 view similar to that shown in Fig. 3, but illustrating a clamping device in released position. Fig. 6 is a detail end elevation of 75 a portion of one end of the ironing table, illustrating the means for operating the movable or stretching clamp-member of the mechanism. Fig. 7 is a transverse section of a portion of said ironing table illustrating a modified means for moving and retaining the movable or stretching clamp-member of 80 the mechanism.

Similar characters of reference are employed in all of the said above-described views to indicate corresponding parts.

Referring now to the said drawings, the 90 reference character 1 indicates the complete combined stretching and ironing table made according to and embodying the principles of the present invention, the same comprising a table-body 2, supported upon suitable 95 standards or legs 3, said table-body 2 being provided with frame-members 4, which depend upon the under-side of said table-body, and which may be connected or suitably joined with said standards or legs 3. 100 Mounted upon the upper surface of said table-body 2 is a suitable padding-material 5, over which extends a covering 6, preferably made of a suitable fabric. Suitably secured to said table-body 2 and a frame-member 4, so as to be arranged adjacent to one longitudinal edge of said table-body, and preferably disposed beneath said edge, are a plurality of bearing-brackets 7, in 105 which is journaled, so as to extend longitudi- 110

dinally, and adjacent to said longitudinal edge of said table-body, a shaft 8. Mounted upon said shaft 8 are a plurality of eccentric-members 9, having hub-portions 10, 5 through which extend set-screws 11, or other suitable means, for fixing said eccentric-members 9 upon said shaft 8. Journaled respectively upon said eccentric-members 9 by their lower ends 12 are upwardly extending carrier-arms 13. Connected with the upper ends of said carrier-arms 13 are forwardly projecting portions 14, which are adapted to extend over a longitudinally disposed clamp-member 15, which is secured to 10 the upper ends of said carrier-arms 13, by means of the lateral perforated ears 16 of said carrier-arms, through which extend any suitable form of fastening means, such as lag-screws 17, or the like. Said clamp-member 15 is preferably made of wood, being composed of laminated strips or layers of wood built up together to provide a proper bulk or body to the same, which owing to such construction is not apt to be 15 warped or otherwise distorted from its necessary straight form, adapted to properly engage the upper surface of said table-body, and to maintain its longitudinal alinement with the edge of the said table-body. The 20 under side of said clamp-member 15 is provided with a suitable padding-material 18, which is preferably covered with a covering 19 of some suitable fabric, or the like. Fixed upon said shaft 8 is a hand-lever 20, 25 whereby the proper oscillation or rotary movement may be imparted to said shaft 8 and said eccentric-members 9 mounted thereon. Said table-body 2 is provided with a longitudinally extending slot or opening 21, in which is mounted a vertically movable 30 carrier-bar 22. Fixed in said carrier-bar 22, so as to project upwardly therefrom, are a plurality of holding-points 23, the free ends of which are sharpened so as to pierce 35 through said padding-material 5 and covering 6 of said table-body, and also said covering 19 and padding-material 18 of said clamp-member 15. Said carrier-bar 22 and its holding-points 23 are so disposed in said 40 slot or opening 21, that they are positioned beneath said clamp-member 15 when the latter is in clamping position. Journaled in said bearing-brackets 7 is another longitudinally extending shaft 24. Fixed upon 45 said shaft 24 are eccentric-members 25, the latter being engaged by the receiving-portions 26 of connecting-rods 27, which are pivotally connected by their upper ends with the said carrier-bar 22. Fixed upon 50 said shaft 24 is a hand lever 28, whereby the proper oscillation or rotary movement is imparted to said shaft 24 and said eccentric-member 25 mounted thereon.

Associated with said table-body 2 is a 55 transversely movable clamp-member, adapt-

ed to extend longitudinally upon the upper surface of said table-body, the same comprising a pair of clamp-members consisting of a lower clamp-member 29 and an upper clamp-member 30, the same being pivotally connected together at their rear edges by means of suitable hinge-members 31. Said lower clamp-member 29 is provided adjacent to its forward edge with a plurality of upwardly extending gripping-points 32. Said upper clamp member 30 is provided at its forward marginal edge with suitable padding-material 33, over which extends a suitable covering 34, preferably made of a fabric. The means for moving transversely upon said table-body said transversely movable clamp-member thus constructed comprises, a shaft 35 journaled in suitable bearing brackets 36, preferably secured to the under side of the opposite longitudinal edge 35 of said table-body to that where the pivoted clamp-member 15 is located. Fixed upon said shaft 35 are drums 37, to which are secured one end of the pull-straps 38, or other suitable flexible connections, the opposite 40 ends of which are suitably secured to said transversely movable clamp-member. Said shaft 35 is provided at one end with a suitable crank-handle 39, by means of which rotary movement is imparted to said shaft 35 and drums. Also fixed upon said shaft 35 is a ratchet-wheel 40, and pivotally mounted on one of said bearing brackets 36, preferably, is a dog 41 which engages or rides upon said ratchet-wheel 40, and prevents 45 any back-slipping of said transversely movable clamp-member when the same is being moved to stretch the article to be ironed, as will subsequently be described. Said dog 41 is provided with a knob 42, or other suitable means, adapted to be received by a spring-detent device 43, which is secured to the under side of said table-body 2, and by means of which said dog may be maintained 50 out of engagement with said ratchet-wheel 40, when it is desired that the shaft and drums be rotated to unwind said pull-straps 38, to permit the positioning of said transversely movable clamp-member for the connection thereof with an article preparatory to the stretching operation.

While the means above described for moving said transversely movable clamp-member during the stretching operations is preferable, I may provide a modified means to accomplish this end, such as is shown in Fig. 7 of the drawings. Such a construction comprises pull-straps 44, or their equivalent, which are secured to said transversely movable clamp-member. Said pull-straps are 125 provided with a plurality of perforations 45. The pull-straps 44 are adapted to be operated by hand, and when the clamp-member has completed its stretching movement, said pull-straps 44 are engaged by one 130

of their perforations 45 upon holding pins 46, which may be located and fixed to any convenient part of the table-body 2, its frame-members 4 or legs 3, as desired, and when said pull-straps are thus retained said clamp-member will be held against yielding to the pull of the stretched article.

The covering 6 of said table body 2 is provided with a suitable longitudinal base line or gage mark 47 and longitudinal gage marks or lines 47', and transverse gage marks or lines 48, with which the edges of the article to be stretched and ironed may be alined to properly dispose the same upon the table with relation to the position and operation of the respective clamp-members.

Having thus described in detail the construction of my novel combined stretching and ironing table, the method of employing the same during the operations of stretching and ironing articles thereon is as follows:— Assume that it is desired to stretch and iron a lace-curtain, or other rectangular shaped article. The said hand-lever 20 is swung upwardly which rotates said shaft 8 and said eccentric-members 9 in such a manner, that the latter produces a lifting or vertical movement of the carrier-arms 13, which raises the clamp-member 15 away from the surface of the table-body 2, whereupon the said clamp-member may be swung outwardly and downwardly. The lace curtain is then laid upon the table-body 2, with one of its longitudinal edges registered with said base-line or gage-mark 47, and the same is smoothed out so that its remaining longitudinal edge and lateral edges register respectively with the nearest longitudinal gage-marks or lines 47' and the transverse gage-marks or lines 48. When the curtain is thus positioned, the clamp-member 15 is turned up over the table-body 2, and then the hand-lever 20 is swung downwardly thus oscillating the shaft 8 and eccentric members 9, the latter thereby causing said clamp-member 15 to move downwardly upon the edge of said curtain, and thus firmly gripping or clamping said edge of the curtain between said clamp-member 15 and the table-body 2. The transversely movable clamp-member is now moved up to the opposite longitudinal edge of the curtain, and its members are opened so that the opposite longitudinal edge of the curtain may be hooked upon said gripping-points 32, whereupon said members are closed, thus firmly gripping said opposite edge of said curtain. Now by rotating said shaft 35, and consequently said drums 37, the pull-straps 38 are wound upon the latter, thus drawing said transversely movable clamp-member rearward, and thereby exerting a stretching pull uniformly through said curtain. When a proper degree of stretching has thus been produced, the shaft 35 and drums 37 are

retained against an opposite or yielding rotary movement by said ratchet-wheel 40 and pawl or dog 41. While the curtain is thus held stretched between the two clamp-members, the heated smoothing irons may be applied thereto, and the ironing operations carried out. After the body of the curtain has been ironed, the said longitudinal edges of the curtain may be released from the respective clamp-members, and the heated smoothing iron run over the same, thus completing the ironing of the curtain.

Frequently curtains and other articles are possessed of scalloped or waving edges. In such cases it is difficult to get the scallops in line, and so maintain them during the stretching operations, therefore I provide means for alining and holding such edges. Preparatory to stretching and ironing such a curtain, I swing upwardly the lever 28 which oscillates the shaft 24 and eccentrics 25, thereby transmitting through connecting-rods 27, an upward vertical movement to said carrier-bar 22, which thrusts said holding-points 23 up through the padding and covering of said table, so that their free ends project above its surface. The clamp-members 15 being swung out of the way, the scalloped edge of the curtain or the like, is laid upon the table, and the apexes of the scallops are hooked over said holding-points 23, then said clamp-member 15 is closed in the usual manner, as above described, thus clamping the edge of the curtain, with the scallops all properly alined and held against slipping out of alinement by the holding-points 23. The transversely moving clamp-member is then engaged with the opposite edge of the curtain or the like, and the stretching and ironing operations performed in the manner already hereinabove described.

Of course, it will be readily understood that many changes may be made in the above described construction of my invention and its detail parts, and many apparently widely different embodiments of my invention could be made without departing from the scope thereof, I intend, therefore, that all matter contained in the above description or shown in the accompanying drawings shall be interpreted as illustrative, and not in a limiting sense. I also desire it to be understood that the language used in the following claims is intended to cover all generic and specific features of the invention herein described and all statements of the scope of the invention, which, as a matter of language, might be said to fall between.

I claim:—

1. In a device of the kind described, a padded table-body provided with a longitudinal opening, a carrier-bar vertically movable in said opening, holding-points 130

carried by said carrier-bar and adapted to be projected above the surface of said table-body, means for producing vertical movements of said carrier-bar, a pivoted clamp-member at one edge of said table-body, and a transversely movable clamp-member mounted upon said table-body parallel to said pivoted clamp-member.

5 2. In a device of the kind described, a padded table-body provided with a longitudinal opening, a carrier-bar vertically movable in said opening, holding points carried by said carrier-bar and adapted to be projected above the surface of said table-body, means for producing vertical movements of 10 said carrier-bar, a pivoted clamp-member at one edge of said table-body, means for producing vertical movements of said pivoted clamp-member, and a transversely movable clamp-member upon said table-body lying parallel to said pivoted clamp-member.

15 3. In a device of the kind described, a padded table-body provided with a longitudinal opening, a carrier-bar vertically movable in said opening, holding-points carried by said carrier-bar and adapted to be projected above the surface of said table-body, means for producing vertical movements of said carrier-bar, a pivoted clamp-member at one edge of said table-body, means for producing vertical movements of 20 said pivoted clamp-member, a transversely movable clamp-member upon said table-body lying parallel to said pivoted clamp-member, and means for producing a transverse movement of 25 said movable clamp-member.

30 4. In a device of the kind described a table-body, bearing-brackets adjacent to one longitudinal edge of said table-body, a shaft 35 journaled in said bearing-brackets, eccentrics fixed on said shaft, carrier-arms journaled on said eccentrics, a longitudinally extending clamp-member carried by said carrier-arms adapted to be projected over the marginal edge of said table-body, means for oscillating said shaft and eccentrics to produce vertical movements of said carrier-arms and said clamp-member, and a transversely movable clamp-member upon said 40 table-body lying parallel to said first mentioned clamp-member.

45 5. In a device of the kind described a table-body, bearing-brackets adjacent to one longitudinal edge of said table-body, a shaft 50 journaled in said bearing-brackets, eccentrics fixed on said shaft, carrier-arms journaled on said eccentrics, a longitudinally extending clamp-member carried by said carrier-arms adapted to be projected over the marginal edge of said table-body, means for oscillating said shaft and eccentrics to produce vertical movements of said carrier-arms and said clamp-member, a transversely movable clamp-member upon said table- 55 body lying parallel to said first mentioned clamp-member.

60 6. In a device of the kind described a table-body, bearing-brackets adjacent to one longitudinal edge of said table-body, a shaft 65 journaled in said bearing-brackets, eccentrics fixed on said shaft, carrier-arms journaled on said eccentrics, a longitudinally extending clamp-member carried by said carrier-arms adapted to be projected over the marginal edge of said table-body, means for oscillating said shaft and eccentrics to produce vertical movements of said carrier-arms and said clamp-member, a transversely movable clamp-member upon said table- 65 body lying parallel to said first mentioned clamp-member, and means for producing a transverse movement of said movable clamp-member.

clamp-member, and means for producing a transverse movement of said movable clamp-member.

6. In a device of the kind described a table-body, bearing-brackets adjacent to one longitudinal edge of said table-body, a shaft journaled in said bearing-brackets, eccentrics fixed on said shaft, carrier-arms journaled on said eccentrics, a longitudinally extending clamp-member carried by said carrier-arms adapted to be projected over the marginal edge of said table-body, means for oscillating said shaft and eccentrics to produce vertical movements of said carrier-arms and said clamp-member, a transversely movable clamp-member upon said table-body lying parallel to said first mentioned clamp-member, and means for producing a transverse movement of said movable clamp-member, comprising bearing-brackets adjacent to the opposite longitudinal edge of said table-body, a second shaft journaled in said bearing-brackets, drums fixed on said shaft, pull-straps coiled on said drums, the opposite ends of said pull-straps being secured to said transversely movable clamp-member, and means for rotating said second shaft.

7. In a device of the kind described a table-body, bearing-brackets adjacent to one longitudinal edge of said table-body, a shaft journaled in said bearing-brackets, eccentrics fixed on said shaft, carrier-arms journaled on said eccentrics, a longitudinally extending clamp-member carried by said carrier-arms adapted to be projected over the marginal edge of said table-body, means for oscillating said shaft and eccentrics to produce vertical movements of said carrier-arms and said clamp-member, a transversely movable clamp-member upon said table-body lying parallel to said first mentioned clamp-member, and means for producing a transverse movement of said movable clamp-member, comprising bearing-brackets adjacent to the opposite longitudinal edge of said table-body, a second shaft journaled in said bearing-brackets, drums fixed on said shaft, pull-straps coiled on said drums, the opposite ends of said pull-straps being secured to said transversely movable clamp-member, means for rotating said second shaft, a ratchet-wheel fixed on said second shaft, and a pivoted dog coöperating with said ratchet-wheel to prevent a reverse rotation of said shaft.

8. The combination with an ironing table having a longitudinal opening therein of a carrier-bar vertically movable within said opening, a shaft journaled below said carrier-bar, means operated by said shaft and connected with said carrier-bar for producing vertical movements of the latter, and holding-points mounted upon said carrier-bar, said holding-points being projected

- above the level of said table by the upward movement of said carrier-bar and being withdrawn below the level of said table by downward movement of said carrier-bar, a clamp-member coöperating with said holding-points, and a second transversely movable clamp-member capable of movement toward or away from said first mentioned clamp-member.
- 10 9. The combination with an ironing table having a longitudinal opening therein of a carrier-bar vertically movable within said opening, a shaft journaled below said carrier-bar, means operated by said shaft and connected with said carrier-bar for producing vertical movements of the latter, and holding-points mounted upon said carrier-bar, said holding-points being projected
- 15

above the level of said table by the upward movement of said carrier-bar and being withdrawn below the level of said table by downward movement of said carrier-bar, a clamp-member coöperating with said holding-points, and a second transversely movable clamp-member capable of movement 20 toward or away from said first mentioned clamp-member, and means for holding said second clamp-member in a position to which it has been moved.

In testimony, that I claim the invention 30 set forth above I have hereunto set my hand this 11th day of December, 1913.

RALPH D. HOWELL.
